UNITED STATES PATENT OFFICE

GEORGE F. HOUSTON, OF SOUTH BEND, INDIANA, ASSIGNOR TO BENDIX RESEARCH CORPORATION, OF EAST ORANGE, NEW JERSEY, A CORPORATION OF INDIANA

PROPELLER

Application filed November 7, 1930. Serial No. 494,109.

This invention relates to propellers and more particularly to means for mounting propeller blades in a hub.

It has heretofore been proposed to construct one-piece hubs for propeller blades, such construction having many and obvious advantages over two-part hubs. In such one-piece hubs it has been usual to attach the propeller blade to the same by means of bolts extending through the hub and blade. However, the attaching means heretofore employed present certain disadvantages among which may be mentioned the difficulty and manipulation involved in positioning the blade to permit the insertion of the bolts. Accordingly, it is one of the objects of the present invention to provide a hub construction for propeller blades which is constituted in such a manner as to avoid the above disadvantages.

Another object of this invention is to provide novel means for attaching a propeller blade to a hub, which means shall become operative upon insertion of the blade into the hub.

Another object is to provide in a propeller construction of the above character novel means whereby the blade may be easily and quickly detached from the hub.

Still another object is to provide a novel propeller hub with means whereby a propeller blade may be automatically locked therein upon insertion of the blade within the hub.

A further object is to provide a one-piece hub for propeller blades, together with means for attaching the blade to the hub, and means for preventing rotation of the blade in the hub.

A still further object is to provide a propeller hub construction characterized by a novel arrangement of parts resulting in a simple and compact structure and wherein the propeller blades may be easily and quickly connected and disconnected therefrom.

Other objects and novel features of the invention will appear more fully hereinafter in the following detailed description taken in connection with the accompanying drawing. It is to be expressly understood, however,

that the invention is not designed as a definition of the limits of the invention, reference being had for this purpose to the appended claims.

In the drawing, wherein like reference characters refer to like parts throughout the several views:—

Fig. 1 is a vertical section of a propeller blade and hub assembly constructed in accordance with the present invention; and

Fig. 2 is a front view of the propeller hub.

A construction embodying the present invention is illustrated as comprising an integrally formed one-piece hub 1, having a plurality of sockets 2 for the reception of the inner or root ends of blades 3 and also having a centrally-disposed opening 4 to receive a keyed drive shaft 5 for rotating the hub.

Means are provided for detachably securing the blade to the hub, and as shown such means comprise annular grooves 6 formed internally of the hub and opening into the blade-root receiving socket thereof. Although two such annular grooves for each hub-receiving socket are disclosed in the drawing, it is to be understood that a greater or less number may be satisfactorily employed if desired. Facing these annular grooves or recesses and formed on the propeller root are similar annular recesses 7, the opposed recesses 6 and 7 forming annular chambers. Means adapted to prevent relative longitudinal movement between the hub and blade are disposed in such annular chambers.

Such means are constituted by split rings 8 and 9 the abutting ends of which are resiliently or yieldably held apart by springs 10 in order that the outer peripheries of such rings will be held in firm contact with the annular grooves 6. The rings 8 and 9 are preferably formed with a trapezoidal cross-section, the outer peripheral surface of such rings having portions 11 in contact with the bottoms of the annular grooves 6, and inclined portions 12, as clearly illustrated in the drawing. The inclination of the inclined portion of the exterior periphery of ring 9 is preferably such that when the blade-root is inserted into the hub socket, the expansion of ring 9 into the outer annular depression 6

in the hub socket will not prevent further insertion of the propeller. To this end the inclination of the inclined peripheral part 12 should extend radially inward of the wall 15 of the hub socket when the ring is in its most expanded condition. It is not necessary that the rings 8 be constructed in this manner but it is desirable that they be so formed in order that the rings may be interchangeable. Instead of accurately machining the inclined portions 12 of the rings 9 to facilitate insertion of the blade into the hub, as described above, such insertion may be effected by threading the screws 13, which are opposite the outer groove 6, inwardly of the hub until their inner extremities are substantially flush with the inner wall of the hub socket. With the screws so positioned the rings 9, on insertion of the blade into the socket, cannot expand into the outer groove 6 in order to lock the blade in the hub. On complete insertion of the blade into the socket, however, it will be understood that the screws 13 are moved outwardly again to permit the ring 8 to expand 25 into locking position in the groove 6.

Means are provided for preventing rotation of the propeller in the hub socket, and as shown, such means include an annular groove 14 formed in the outer surface of the hub 14 and adjacent the outer extremity thereof. Disposed in such groove is a collar 15 having ears 16 formed on the ends thereof, the same being formed with aligned holes 17 for the reception of a headed bolt 18 which is screw threaded at its end to receive a nut 19. In order to permit such tightening means to contract the hub about the propeller root to frictionally grip the latter, longitudinal slots 20 are formed in the outer extremity of each hub, there being, preferably, two such slots in each hub socket, the same being diametrically opposed. When the propeller has been inserted in the hub socket the nut 19 is turned to tighten the collar 15 in the groove 14, thereby contracting the extremity of the hub socket about the propeller root by reason of the play afforded by the slots 20.

Means are provided for contracting the split rings 8 and 9, such contraction being necessary in order to effect removal of the blade from the hub. As hereinbefore stated, when the parts are in their assembled position, the rings 8 and 9 are expanded outwardly into the recesses 6 by means of the springs 10 which are disposed between their ends. Such rings 8 and 9 must be contracted wholly into the grooves 7 in order that the blade may be withdrawn from the hub, the means provided for effecting such contraction comprising screws 13 threadedly received in suitable openings provided in the wall of the hub, said screws 13 abutting the flat portions 11 of the rings 8 and 9. Two such screws are preferably provided for each ring, as is shown, but a greater number may

be employed if desired. When it is desired to withdraw the blade from the socket the screws 13 are turned to move them radially inward of the hub to thereby abut and contract the rings 8 and 9 against the tension of springs 10. When such rings are contracted so that their exterior peripheries are entirely interior of the hub socket the blade may be withdrawn from the socket.

It will be evident from the foregoing description that the present invention provides novel and improved means for attaching a propeller blade to a hub. Such means are automatically operable on complete insertion of the propeller blade into the hub to prevent relative longitudinal movement between the hub and blade. The attaching means is simple in structure and easily operable, it being necessary only to insert the blade into the hub when the expanding rings have been placed in position on the blade. Means have also been provided for effecting release of the blade from the hub, such means being simple, efficient and positive in operation. The invention also provides means for preventing rotation of the blade in the hub, such means being operable by a very simple mechanism.

While certain specific features of this invention and parts incident thereto have been illustrated and described in detail, it will be apparent that the invention is capable of embodiment in various forms as will now occur to those skilled in the art, without departing from the scope of the invention. Reference is therefore to be had to the appended claims for a definition of the limits of the invention.

What is claimed is:

1. A propeller blade, a hub therefor comprising a cylindrical member having a plurality of spaced, annular grooves internally thereof, an external groove at the free end of said hub adapted to receive a clamping ring, external annular grooves on said propeller blade adapted to register with the said internal grooves of said hub to form a recess therewith, and spring-actuated expansion rings adapted to be received in said recess to releasably prevent relative movement of said propeller blade and hub.

2. A propeller blade, a hub therefor having internal annular recesses therein, external annular recesses formed on said blade, and yielding means disposed within said last-named recesses and adapted to be expanded into said first-named recesses to thereby prevent relative longitudinal movement between said hub and said blade.

3. A propeller blade, a hub therefor comprising a cylindrical member having a plurality of spaced, annular grooves internally thereof, external annular grooves on said propeller blade registering with said internal grooves of said hub to form recesses, and expandable means adapted to be received in said

recesses to releasably prevent relative longitudinal movement between said propeller and hub.

4. In a propeller, a propeller hub having a socket, a propeller blade adapted to be inserted in said socket and means for connecting said blade and said socket, said means including an expandable and contractible member.

5. In a propeller blade and hub construction, means automatically actuated by insertion of the blade into the hub to attach said blade to said hub, and means for permitting release of said blade from said hub, said last-named means being disposed in said hub and cooperating with said first named means.

6. A propeller blade, a hub therefor, means formed in said hub and adapted to coact with means on said blade for detachably attaching said blade to said hub, and means disposed in said hub and coacting with said second-named means to permit detachment of said blade from said hub.

7. A propeller blade having annularly-disposed means thereon, a hub for said blade having means formed therein to coact with said first-named means, said means on said blade being actuated on complete insertion of said blade into said hub to attach said blade to said hub.

8. In a propeller, a blade, a hub, means on the blade for insertion into the hub, and means automatically actuated by insertion of the blade into the hub for securing the blade thereto.

9. In a propeller blade and hub construction, the combination with means on the blade for insertion into the hub, of means disposed on said first-named means and actuated by complete insertion of said blade into said hub for attaching said blade thereto.

10. In a device of the class described, a propeller blade, a hub, resilient means disposed on said blade, and means formed in said hub to receive said resilient means on complete insertion of said blade in said hub to thereby attach said blade to said hub.

11. A propeller blade, a hub to receive said blade, expandable and contractible rings on said blade, annular recesses formed in said hub, said rings being adapted to be received into said recesses on complete insertion of said blade into said hub to thereby detachably attach said blade to said hub.

12. A propeller blade, a hub to receive said blade, means disposed on said blade and adapted to coact with means formed in said hub to detachably attach said blade to said hub, and screw-threaded means for permitting detachment of said blade and said hub.

13. In a propeller blade and hub construction, separate means adapted to coact to releasably prevent detachment of said blade and hub, one of said means being expandable and

contractible, and means for effecting contraction of said expandable and contractible means for detaching the blade from the hub.

In testimony whereof I have signed this

70

GEORGE F. HOUSTON.
